Specification for Design.

Patented July 10, 1917.

Application filed April 25, 1917. Serial No. 164,557. Term of patent 14 years.

To all whom it may concern:

Be it known that I, CHARLES L. DEPOLLIER, a citizen of the United States, residing in the borough of Brooklyn, of the city of New York, in the State of New York, have invented a certain new and ornamental Design for a Watch-Bow, of which the following is a specification, reference being had to the accompanying drawing, forming a part hereof.

In said drawing,

The figure is a view in front elevation of the improved watch bow.

I claim the ornamental design for a watch bow, as shown.

Signed this 16th day of April 1917.

CHARLES L. DEPOLLIER.
